DESIGN FOR A DRESS

Cele Frankel, New York, N. Y.

Application March 6, 1940, Serial No. 90,703

Term of patent 3½ years

To all whom it may concern:

Be it known that I, Cele Frankel, a citizen of the United States and a resident of the city of New York, in the county of Bronx and State of New York, have invented a new, original, and ornamental Design for a Dress, of which the following is a specification, reference being had to the accompanying drawing, forming a part thereof.

Fig. 1 is a front view of a dress showing my new design.

Fig. 2 is a rear view of the dress as shown in Fig. 1.

The characteristic feature of my design resides in the design of the lace trim extending around the square neck line and down the front at one side from the square neck line, terminating just below the waist line in association with the same lace trim at the end of the short sleeves in combination on the specific dress as shown.

I claim:

The ornamental design for a dress, substantially as shown and described.

CELE FRANKEL.
